FLOODLIGHT

Charles H. Oppenheimer, Shaker Heights, Ohio,
assignor to Enterprise Electric Lighting Fix-
tures, Inc., Cleveland, Ohio, a corporation of
Ohio

Application August 26, 1932, Serial No. 630,564

3 Claims. (Cl. 240—3)

This invention relates to a floodlight especially adapted for use in show windows and similar places.

The principal object of the invention is to provide a simple and effective device of this character which will accomplish the two functions by the use of a device occupying a minimum of space and by means of which new and desirable lighting effects may be had. A more limited object is the provision of a combined device of this character comprising two compartments separated by a partition which serves the double function of illuminating a translucent sign by reflected light and forming a portion of the floodlight compartment giving to such compartment a desirable shape.

A still further object is the provision of means for securing a spotlight effect on articles displayed in the show window or by simple manipulation destroying such effect and giving more nearly uniform lighting.

Other and more limited objects will become apparent from the following description when taken in connection with the accompanying drawings in which Fig. 1 is a front elevation of a device embodying my invention; Fig. 2 is a transverse section taken therethrough; Fig. 3 is a section on the line 3—3 of Fig. 2 and Fig. 4 is a detail elevation of one of the lenses.

In the drawings the numeral 10 indicates the bottom wall of a casing having a front wall 11 the lower portion of which is formed by a translucent sign 12, a top wall 13 and an inclined rear wall 14 provided with a plurality of lenses 15. The sign 12 may be mounted between the wall 11 and offset members 16, provision being made for sliding the sign in from one end whereby it may be changed, if desired. The bottom wall 10 may be continuous with a portion 17 of the wall 14 turned back to provide a channel between itself and a bottom strip 18 removably secured thereto as by a thumb screw 19. Extending from the lower front corner to the upper rear corner of the casing is a partition 20 which may be continuous with a portion 21 of the front wall 14 whereby to complete the mounting for the lenses 15. The front surface of the partition 20 is highly polished or otherwise provided with a reflecting surface.

Mounted above the sign 12 in the sign compartment S as by brackets 22 are a plurality of sockets 23 receiving electric bulbs 24 and energized by suitable electric connections 25 to a source of current 26. Inasmuch as the lamps 24 are positioned above the sign 12 only a small amount of

light therefrom will fall directly upon the sign. However, the rays from these lamps will be reflected from the reflecting surface of the partition 20 and illuminate the sign 12. The sign may be opaque and provided with a translucent design 60 or translucent and provided with an opaque design.

Suitably mounted within the floodlight compartment F is a tubular shaft 27 having mounted on one end thereof outside the casing a knob 28 65 by which it may be rotated through a small angle. Between the knob 28 and the end wall of the casing is provided a spring washer 29 adapted to cooperate with the knob and a similar spring washer 30 between the opposite end wall and 70 a collar 31 on the shaft 27 to hold the shaft 27 frictionally in any adjusted position. Rigidly mounted upon the shaft 27 are a plurality of arms 32 carrying sockets 33 for bulbs 34. Electrical connections 35 may extend from the sockets 34 75 to a source of current 36 brought in through the tubular shaft 27. The conductors 35 may pass through suitable openings 37 in the shaft. Each of the bulbs 34 may have secured thereto a hemispherical reflector 38 adapted to direct a large 80 portion of the light toward the lens 15. These reflectors may be secured to the bulbs in any suitable manner as by springs 39 and 40 passing therearound.

Each of the lenses 15 is provided with a plurality of concentric ridges 15^a surrounding its center. When it is desired to give a spotlight effect or brilliant illumination to some particular object in the show window, a bulb 34 is positioned immediately behind the center of the lens 15 85 in alignment with the object so to be illuminated. If the knob 28 is actuated to position the bulbs 34 eccentrically of the lenses 15 the result will be greater diffusion of the light, the spotlight effect gradually disappearing as the bulb is 90 positioned further from the center of the lens. The lens 15 is what is known as a Fresnel lens but the lens shown in the drawings is not to be regarded as a detail showing of the prisms.

From the foregoing it will appear that I have 100 provided a simple device which is well adapted for its intended purpose and while I have shown and described the preferred embodiment of my invention I wish it understood that I am not limited to the details of the disclosure except in 105 accordance with the spirit and scope of the appended claims.

Having thus described my invention, what I claim is:

1. A floodlight for show windows comprising 110

- in combination a casing having a backwardly inclined face provided with a Fresnel type lens, a bottom, an oppositely inclined wall forming with said bottom an angle opposite said lens, the surface of the said wall adjacent said lens having a light reflecting surface, a plurality of lamps disposed between said lens and said inclined wall and means for moving said lamps laterally of said lens toward and from a position opposite the center thereof.
- 10 2. In a floodlight for a show window, a casing, a Fresnel type lens forming one wall of said casing, a shaft mounted within said casing and accessible from the exterior thereof, a plurality of 15 lamps disposed behind said lens and operatively

connected with said shaft, means for rotating said shaft whereby to position said lamps at, above or below the center of said lens whereby to give optionally a spotlight effect or upwardly or downwardly preponderating diffused lighting.

80

3. A show window floodlight comprising in combination a casing having an inclined face provided with a Fresnel type lens, a plurality of lamps arranged within said casing and means for simultaneously moving all of said lamps toward and away from the center of said lens whereby to produce a spotlight effect or diffused illumination.
